UNITED STATES PATENT OFFICE.

JOHN B. NESMEYER, OF OMAHA, NEBRASKA.

PULLEY-BLOCK.

1,876,457.

Specification of Letters Patent.

Patented May 3, 1921.

Application filed April 10, 1920. Serial No. 372,773.

To all whom it may concern:

Be it known that I, JOHN B. NESMEYER, a citizen of the United States, residing at Omaha, in the county of Douglas and State 5 of Nebraska, have invented certain new and useful Improvements in Pulley-Blocks, of which the following is a specification.

This invention relates to improvements in hoisting devices and more particularly to 10 blocks of the multiple sheave type.

An important object of this invention is to provide a block of the multiple sheave type having novel means whereby the shackle of the same may be readily and conveniently removed to permit the fall line or 15 tackle to be wound about the sheaves.

The invention further aims to provide a block and tackle having novel means whereby the strain imparted to the shaft or pin 20 supporting the sheaves may be transmitted through the sheaves to a plurality of rollers carried by the block.

The invention still further aims to provide a block and tackle which is of highly 25 simplified construction, desirable in use and cheap to manufacture.

Other objects and advantages of the invention will be apparent during the course of the following description.

30 In the accompanying drawing forming a part of this application and in which like numerals are employed to designate like parts throughout the same,

Figure 1 is an elevation of the improved 35 block and tackle in use.

Fig. 2 is a central vertical section through the improved block.

Fig. 3 is a vertical transverse section taken on line 3—3 of Fig. 2.

40 In the drawing wherein for the purpose of illustration is shown a preferred embodiment of the invention, the numeral 5 generally designates the improved block which, as particularly illustrated in Fig. 2, comprises a plurality of spaced parallel plates indicated by the numerals 6, 7, 8 and 9. A plurality of sheaves, indicated by the numerals 11, 12 and 13, are arranged between the spaced parallel plates 6, 7, 8 and 9 and 45 are provided with axially arranged bushings 14 which receive a centrally arranged pivot pin 16 extended through aligned openings 17 in the said spaced parallel plates. The end portions of the shaft or pivot pin 50 16 are provided with transverse openings

which receive locking devices 18 in the form of retaining keys, or the like.

With reference to Figs. 2 and 3, it will be noted that the lower portions of the plates 6, 7, 8 and 9 are provided with ears 20 which receive a transversely extending pin 21 having spacing collars 22 confined between the plates 6, 7, 8 and 9, so as to properly space the said plates.

A pair of connecting pins 24 are extended 65 through the ears 20 of the several plates and are arranged on opposite sides of the connecting pin 21 in spaced parallel relation to the same. The connecting pins 24 which are arranged in spaced parallel relation to each 70 other carry anti-friction rollers 26 which are engaged by the peripheries of the sheaves during the rotation of the latter, so that as the sheaves are rotated the strain transmitted through the same will be taken up by the 75 connecting pins 24. By this construction the weight being hoisted is prevented from imparting any undue strain to the shaft 16. With reference to Fig. 3, it will be observed that the anti-friction elements 26 and consequently the connecting pins 24 are arranged 80 on opposite sides of the vertical center of the block so that, regardless of the direction of rotation of the several sheaves, the rollers will be in a position to support the sheaves 85 in co-operation with the shaft 16.

The upper portions of the plates are also formed with apertured ears 30 through which is extended a detachable connecting pin 31. The pin 31 is provided at one end 90 portion with transverse opening receiving a detachable locking device 32 which may, if desired, be in the form of a cotter pin. In addition to connecting the upper ends of the spaced parallel plates, the detachable 95 connecting pin 32 serves as a means for detachably securing a shackle 34 to the several plates. As illustrated in Fig. 2, the shackle 34 is formed with a plurality of aligned barrels 35 having bushings 36 rotatably and 100 detachably receiving the transverse connecting pin 31. The block may be attached to a suitable support by a clevis 38 pivotally connected to the shackle by a pivot bolt 40.

105 In the use of the improved block a flexible hoisting element 42 may be arranged about the several sheaves by merely detaching the shackle. With the shackle thus detached the flexible element 42 may be freely wound about the several sheaves without interfer- 110

ence by the shackle or the pivot pin 31. The flexible element 42 is of course passed about the several sheaves after one end of the same has been connected to a loop 45 5 carried by one of the sleeves 22. As illustrated in Fig. 1, a bracing strap 46 is disposed vertically on the outer sides of the plates 6 and 9 and is provided intermediate its ends with transverse openings which receive the end portions of the sheave supporting shaft 16. The end portions of the bracing straps 46 are formed with openings which receive the pins 31 and 21.

10 In lifting weighted objects the fall or flexible element 42 may be positioned at any angle with relation to the line of pull and will not cause undue strain on the parts of the device. A second block 50 of any desired type may be employed in connection with 15 the improved block 5 or if desired the block 20 50 may be similar in construction to the block 5.

With reference to the foregoing description taken in connection with the drawing 25 it will be observed that a block constructed in accordance with this invention is possessed of great strength in proportion to its size and operates with a minimum of effort on the part of the operator.

30 It is to be understood that the form of the invention herewith shown and described is to be taken as a preferred embodiment of the same and that such minor changes in construction and arrangement of parts 35 may be made as will remain within the spirit of the invention and the scope of what is claimed.

Having thus described the invention, what is claimed as new is:

40 1. A device of the class described comprising

ing a plurality of spaced parallel plates, a connecting pin extending through the lower portions of said plates, spacing elements carried by said pin, anti-friction elements arranged on opposite sides of said spacing 45 elements and confined between said plates, and sheaves rotatably arranged between said plates and engaging said anti-friction elements.

2. A device of the class described comprising 50 a body, a sheave carried by the body, and a plurality of anti-friction elements engaging the periphery of said sheave.

3. A device of the class described comprising 55 a plurality of spaced parallel plates, a shaft extending through the central portions of said plates, sheaves mounted on said shaft and arranged between said plates, a pair of spaced parallel pins extending through the lower portions of said plates on opposite 60 sides of the vertical center of the same, and anti-friction elements carried by said spaced parallel pins and engaging the peripheries of said sheaves.

4. A device of the class described comprising 65 a plurality of spaced parallel plates, a shaft extending through the central portions of said plates, a plurality of sheaves mounted on said shaft and confined between said plates, a pin extending through the 70 lower portions of said plates, spacing elements carried by said pin and confined between said plates, a pair of spaced parallel pins arranged on opposite sides of said first named pin, anti-friction rollers carried by 75 said pin and engaging the peripheries of said rollers, and a shackle detachably carried by said plates.

In testimony whereof I affix my signature.
JOHN B. NESMEYER. [L. S.]
